IGNITION SYSTEM.

1,168,314.

Specification of Letters Patent. Patented Jan. 18, 1916.

Application filed November 3, 1910. Serial No. 590,442.

To all whom it may concern:

Be it known that I, CHARLES F. KETTERING, a citizen of the United States, residing at Dayton, county of Montgomery, and State 5 of Ohio, have invented certain new and useful Improvements in Ignition Systems, of which the following is a full, clear, and exact description.

This invention relates to improvements in 10 ignition systems and has among its objects to provide means for dissipating the inductive currents which may arise in the secondary circuits adjacent to the circuit of the cylinder ready to fire, where the sparking 15 impulses are produced by a series of adjacent spark coils.

It has heretofore been proposed to prevent inductive currents from passing from one such coil to another, by the interposition 20 of magnetic shields.

The present invention dispenses entirely 25 with the need of any such devices for obstructing the passage of the inductive influence to the adjacent circuit. The free passage of any such influence from one coil to its adjacent coil is entirely permitted, but the effect is eliminated by dissipating any such inductive current in case it should arise.

With these and incidental objects in view, 30 the invention consists in certain novel constructions and arrangements, a preferred form of which is shown in the drawings accompanying this specification.

In the drawings Figure 1 is a diagrammatic view of the circuits connected with 35 these improvements. Figs. 2 and 3 are detail views of the timer or make and break device which successively breaks the current in the respective primary coils and thereby 40 cause the successive sparking in the secondary circuits. Figs. 4 and 5 are detail views of the make and break part of said timer.

In Fig. 1 the battery 20 is grounded on one side by the wire or conductor 21, and 45 the other side is connected by wire 22 to the various induction coils which may be of the vibrating type as presently described. Each of these coils comprises primary coil 23, wound upon a core 24 and connected by 50 the wire 25 to the make and break armature 26. This armature 26 normally closes contact at the point 27, to close the battery circuit through the common wire 28. The secondary coil 30 is likewise wound on the core 55 24 and is grounded at 31 to the primary cir-

cuit, and at the other end is connected to the spark plug 32 which is grounded in a well known manner.

The lower end of the primary coil 23 is connected by a wire 33 to a switch lever 34, the exact construction of which in the actual apparatus will presently be described. This switch lever 34 normally makes contact with the contact point 35 connected by wire 36 to a common short-circuiting wire 37. When 65 however the switch lever 34 is swung over to dotted line position, shown for the left hand coil in Fig. 1, it makes contact with another contact point 40 which is grounded by a common ground wire 41.

It will be seen that the construction of each of the vibrating coils is similar to that just described, being connected by the wire 28, the common short-circuit wire 37, and the common ground wire 41. Condensers 50

are shunted around the make and break point 27 in a well known manner. In the operation of these devices the timer is so arranged that in rotating it operates in turn upon the four switch arms 34, moving said 60 arms in turn to the dotted line position of Fig. 1. When, for example, the switch-arm 34 for the left hand coil is moved into contact with the point 40, as shown in Fig. 1, the result is that the battery current flows 65 through the wire 22, common wire 28, contact point 27, armature 26, wire 25, primary coil 23, wire 33, switch 34, contact point 40 and common ground wire 41, thus completing 70 the battery circuit through the first primary coil. When the switch 34 of this coil is moved to its dotted line position, all the other switches of the three remaining coils 75 remain in the full line position with the primary windings of said coils short-circuited 80 upon themselves. The timer having operated the switch 34 in this manner, the primary coil 23 is then energized and the armature 26 caused to vibrate in the usual manner, to produce a succession of sparks by 85 excitation of the secondary coil 30. Then the rotary timer revolves to the next switch arm, displacing it to its contact point 40 so as to energize its primary coil in the manner just described, the switch 34 of the first coil 90 having at the same time returned to its normal position in contact with the point 35. In this manner the timer in rotating energizes the successive primaries and secondaries in turn. It will be seen however that 95

100 the switch 34 of the first coil having at the same time returned to its normal position in contact with the point 35. In this manner the timer in rotating energizes the successive primaries and secondaries in turn. It will be seen however that 110

when, for example, the switch 34 of the first coil is in dotted line position so as to energize its primary 23 and secondary 30, the switches 34 of the adjacent coils stand resting in contact with their points 35. The result of this is that all of the other primary coils although open circuited are nevertheless short-circuited upon themselves. That is, there is a complete circuit through the common wire 28, armature 26, coil 23, wire 33, point 35, and common wire 37. Therefore if when the spark occurs in the first coil, there were any inductive influence arising in the adjacent coil, any such inductive current would be dissipated by reason of the fact that the primary of the adjacent coil is short-circuited in this manner. The result of this is to prevent premature sparking in the cylinder adjacent to the cylinder ready for firing and thus to prevent the ill effects arising from this cause.

A desirable form of timer to effect the control of the switch arms 34 in the manner described, is illustrated in Figs. 2 and 3. The cylindrical and hollow casing 60 has journaled in it the rotary timer shaft 61 carrying the rotary arm 62. Attached to the sides of the casing 60 are four binding posts 63 to which are attached the ends 30 of the aforesaid wires 33 referred to in diagrammatic Fig. 1. These wires are the lead wires from the respective primary coils. The inner ends of these binding posts 63 are connected to the metal arms 34 which correspond to the switch arms 34 referred to in connection with Fig. 1. There are four of these switch arms 34 for the four primary coil wires 33, and they normally stand pressing upward under their spring tension 40 against the contact pins 35 corresponding to the contact points 35 of Fig. 1. These pins 35 are seated in the metal cap 64 which is thus electrically connected to the binding post 65 to which is attached the lead wire 37 45 constituting the common short-circuiting wire referred to in connection with Fig. 1. Thus all of the switch arms 34 would normally stand making contact with the pins 35 and thus short-circuiting the primary coils. 50 The rotary contact arm 62 however breaks the contact between the arm 34 and pin 35 in turn in the manner now described. The outer end of this arm, as shown in Fig. 4, is made with an insulating portion 70 and a 55 conducting portion 71, the insulating portion preceding the other in direction of rotation as shown by the arrow in Fig. 4. The conducting portion 71 is of course connected to the main metal portion of the rotating arm 62 and thereby grounded to the framework of the engine. This corresponds to the grounding wire 41 of diagrammatic Fig. 1.

Thus when the rotary arm 62 revolves, the 65 insulating portion 70 first strikes the switch

arm 34 and moves it to break contact as shown at the left in Fig. 3, and then the conducting portion 71 slides into contact with the strip 34, thus connecting said strip with the arm 62 and grounding the same. 70 This corresponds to shifting of the switch 34 to dotted line position, shown in Fig. 1, the breaking of the contact at the point 35 occurring before the grounding of the circuit. 75

From the above, it will be seen that as the arm 62 revolves, it establishes the circuit from the battery 20 to each of the four primary coils in succession, by successively moving the switch elements 34 from the points 35, and immediately thereafter establishing a ground connection therewith. As the battery current flows through each primary, the armature 26 vibrates in the usual manner, thereby permitting a succession of current impulses to traverse the primary winding. During this action, the short circuit around said primary is open.

The high tension impulses in the secondary circuits are induced in the usual manner. 90

The impulses in the primary tend to induce alternating current surges in the primary, and particularly in the secondary windings of the adjacent coils. All of said coils, 95 however, are short-circuited upon themselves. As a result of this, as the induced current in any secondary circuit or coil tends to build up, a magnetic field tends to establish itself through the core, which field induces current in the primary winding, which latter current builds up slowly, due to self-induction, thereby in turn exerting a retarding effect on the magnetic field of the core. This in turn retards the secondary 100 current to such a degree that instead of building up instantaneously to cause a disruptive discharge at the contacts, said induced current is retarded and never attains a sufficiently high voltage to break down the 110 air gap. The energy is thus dissipated without firing the adjacent cylinder.

The ends of the switch arms 34 are preferably beveled or rounded, as shown in Figs. 3 and 5, in order that the ends of the rotating contact arm may easily ride over and depress the strip. 115

While the form of mechanism shown herein is well adapted to accomplish the purposes sought, it is to be understood that this is merely a preferred form of embodiment of the invention and that other forms might be adopted all coming within the scope of the claims which follow.

What is claimed is as follows:— 125

1. In an ignition system, the combination with a plurality of induction coils including iron cores, primary and secondary coils and circuits, spark terminals in the secondary circuits and a main source of current for the 130

- primaries; of means for normally short-circuiting each of said primary coils to dampen any current induced in the secondary coils; and means for successively breaking the short circuit of each primary and concomitantly connecting that primary with the main source of current whereby to energize that primary and prevent any dampening effect therein.
10. 2. In an ignition system, the combination with a plurality of induction coils including iron cores, primary and secondary coils and circuits, spark terminals in the secondary circuits and a main source of current for the primaries; of switch mechanism and connections for said primaries normally short-circuiting the same to dissipate any current induced in the secondary coils; and a common member for engaging said switch mechanism and constructed to break the short-circuit of each primary in turn and at the same time connect that primary with the main source of current whereby sparking impulses will be induced in the secondary circuit of the said primary.
3. In an ignition system, the combination with a plurality of induction coils including primary and secondary coils and circuits, spark terminals in the secondary circuits and a main source of current for the primaries; of a switch and connections for each of said primaries normally short-circuiting the same, said switches being located in proximity to each other; a rotary controlling member rotating in the range of all of said switches; an insulated arm connected with said rotary member and positioned to engage said switches and break said short circuits in turn; and a conducting arm adjacent to said insulated arm and connected with said rotary member, said conducting arm being electrically connected with said main source of current and positioned to engage the switches and connect the same with said main source of current.
4. In an ignition system, the combination with a plurality of induction coils including iron cores, primary and secondary coils and circuits, spark terminals in the secondary circuits; of a main source of current for the primaries; of means for preventing premature sparking in the cylinders, including devices for normally short-circuiting said primaries and adapted to dampen the building up of induced currents in the secondary coils.
5. In an ignition system, the combination with a plurality of induction coils including primary and secondary coils and circuits, sparking terminals in the secondary circuits and a main source of current for the primaries; of switches and connections for said primaries normally short-circuiting the same, said switches being located in proximity to each other; a rotary controlling member rotating in the range of all of said switches, having an arm comprising an insulated portion, provided with a beveled approach to facilitate the engagement of the switches; and a conducting portion for concomitantly establishing the main circuit through the switches.
6. In an ignition system, the combination with a plurality of induction coils, including primary and secondary coils and circuits, sparking terminals in the secondary circuits; and a main source of current for the primaries; of switches each including a movable depending pin; coöperating contact strips normally in engagement with said contact pins for normally short-circuiting the primary circuits; a rotary controlling member rotating in the range of all of said switches, including an arm having an insulated portion adapted to initially engage said depending pins successively and to separate them from their contact position with their normal coöperating contact strips; and means for concomitantly establishing a main circuit through the switches as the normal contacts, thereof, are successively broken.
7. In an ignition system, the combination with a plurality of induction coils having primary and secondary windings, of a main source of current for the primaries, means normally open-circuiting each primary winding and maintaining a closed circuit about the same, and means for successively establishing the circuit of said primaries and concomitantly opening said closed circuit whereby as each primary winding is energized the remaining primary windings act as dampening devices to retard the establishment of high potential induction currents in the corresponding secondaries.
